UNITED STATES PATENT OFFICE.

RICHARD WENSLEY, OF DENVER, COLORADO.

DRUM TRAP.

Application filed October 11, 1926. Serial No. 140,835.

This invention relates to improvements in drum traps of the type described and claimed in United States Letters Patent No. 839,240, issued to me on December 25, 1906.

5 This type of trap is extensively used by plumbers in the installation of bath room fixtures and for other similar uses.

It is the object of this invention to provide a trap having a lead body provided 10 with an open top and with a screw cap for closing the same. An internally threaded ring is secured to the body of the trap at the opening and the removable cap has an external thread that cooperates with the internal threads of the ring.

15 One object of this invention is to provide a fluid tight seal between the body of the trap and the cap so as to protect the threads from the corrosive action of the gaseous 20 contents of the trap.

It is a further object of this invention to produce a trap in which a satisfactory seal is obtained without the use of a separate packing washer.

25 It is a still further object of this invention to produce a construction in which the maximum sized opening can be obtained for any given diameter of trap and thereby produce a trap that can be more conveniently 30 installed than traps of the same size differently constructed.

The above and other objects that may become apparent as this description proceeds are attained by means of a construction and 35 arrangement of parts that will now be described in detail, reference for this purpose being had to the accompanying drawing in which the preferred construction has been illustrated and in which:

40 Fig. 1 is a side elevation of the trap with the cover in place;

Fig. 2 is a vertical diametrical section through the trap;

Fig. 3 is a fragmentary section similar to that shown in Fig. 2, but to a larger scale, the cover being shown in partly closed position; and

50 Fig. 4 is a section similar to that shown in Fig. 3 but to a still larger scale and shows the cover in sealing position.

Let numeral 5 designate the body of the trap, which, as heretofore indicated, it will be assumed, is composed of lead or similar soft metal. A ring 6, which is preferably 55 composed of brass, is provided with an interiorly projecting flange or ledge 7. The

interior surface of this ring, above the flange is threaded as shown at 8 to engage exterior threads on the depending flange 9, which is formed on and constitutes an integral portion of the cap or closure 10.

For the purpose of connecting the body of the trap with the ring 6, the upper end of the body is carried inwardly until its outer diameter is the same as the interior diameter 65 of the flange 7. This permits the ring 6 to be put into place with the interior of flange 7 in contact with the exterior of the body. The extreme upper portion of the body is then bent outwardly on top of flange 70 7 and pressed or spun against the threaded portion of the ring. The lower edge of the depending flange 9 of the cap or closure 10 is provided with a thin edge 12 adapted to indent the portion 13 of the body of the 75 trap which lies above the flange 7. The part 13 of the body of the trap really forms a packing washer and is an integral part of the body.

In order to close the trap it is only necessary to screw the cap 10 into the ring 6 a sufficient distance to bring the sharp edge 12 into contact with the soft metal part 13 of the trap. This makes a fluid tight joint and prevents the contents of the trap from coming 80 in contact with the threads.

I will now call particular attention to one feature of the construction that is of great importance and to which this invention is particularly directed. In the installation of 90 traps of this kind, the plumber is required to attach certain pipes to the body member, this makes it necessary for him to insert his hand into the trap. It is therefore necessary that the smallest internal diameter shall be 95 sufficient to permit a large hand to be inserted and removed. To increase the diameter of the whole trap will, of course, make it possible to obtain the required minimum diameter but this will add to the size 100 and cost of the trap. It is evident that by making the difference between the internal diameter of the body member and the diameter at the neck or diameter D (Fig. 4), as small as possible, the desired results may be 105 obtained with the minimum amount of material. In order that diameter D shall be as large as possible, I have formed the sharp edge 12 of flange 9 as near to the outside as possible. The maximum diameter of the 110 edge 12 that is practicable is the root diameter of the threads on the outside of the

flange. If the cutting edge 12 should be made larger than this, it would intersect the sides of the threads and could not be made continuous. By constructing the lower end 5 of the flange with the edge 12 in line with the cylindrical surface representing the root diameters of the threads, the internal projection of flange 7 can be made as small as desired and the diameter D will thereby be 10 made larger than it would be possible to make it if the diameter of the cutting edge were smaller.

Having described the invention what is 15 claimed as new is:

15 A structure of the class described, having a cylindrical member formed from soft metal, one end of which is closed and forms the bottom and the other end of which is

open, an internally threaded ring surrounding the upper portion of the body of the 20 structure and having an interiorly projecting flange over which the top of the structure is bent and a cap or closure having a depending flange externally threaded to engage the interior threads of the ring, the 25 bottom of the flange of the cap being provided with a thin edge adapted to indent that portion of the body of the structure which is engaged by the flange of the ring, 30 said thin edge having a diameter substantially equal to the root diameter of the threads on the depending flange, and formed in part by a continuation of said external thread.

In testimony whereof I affix my signature.

RICHARD WENSLEY.
